(57) **CLAIM**

The lockable hinge, as shown and described in the foregoing.

DESCRIPTION

FIG. 1 is a perspective view of the lockable hinge of the present invention;

FIG. 2 is a left side of the lockable hinge of the present invention shown in FIG. 1;

FIG. 3 is a right side of the lockable hinge of the present invention shown in FIG. 1;

FIG. 4 is a side view of the lockable hinge of the present invention in the direction of lines 4-4 as represented in FIG. 3;

FIG. 5 is the opposite side view of the lockable hinge of the present invention in the direction of lines 5-5 as represented in FIG. 3;

FIG. 6 is a top or plan view lockable hinge of the present invention in the direction of lines 6-6 as represented in FIG. 2; and,

FIG. 7 is a bottom view of the lockable hinge of the present invention in the direction of lines 7-7 as represented in FIG. 2.
